ATTORNEY.

UNITED STATES PATENT OFFICE.

EDWARD F. YOUNGS, OF WEST CAMP, NEW YORK.

ELECTRICAL TYPE-WRITING MACHINE.

SPECIFICATION forming part of Letters Patent No. 449,923, dated April 7, 1891.

Application filed May 26, 1890. Serial No. 353,165. (No model.)

To all whom it may concern:

Be it known that I, EDWARD F. YOUNGS, a citizen of the United States, residing in West Camp, in the county of Ulster and State of New York, have invented certain new and useful Improvements in Electrical Type-Writing Machines, of which the following is a specification.

My invention relates to means for utilizing electricity as a motive power for operating that class of type-writing machines in which the types are carried on a plate or a type-wheel which is moved in various directions to bring the proper type into position to be struck by a hammer or plunger to print the desired character; and the object of my invention is to produce improved mechanism whereby a circuit-closer at the end of the lever which travels over the character-index, and which moves the type-wheel to locate the proper type in position, will cause the hammer or plunger to be electrically operated to strike the type and print the desired character. By this means the hand which operates the indicator-pointer lever can also cause the character to be printed, thus leaving the other hand free for other purposes, such as operating the spacing-lever.

Referring to the accompanying drawings, Figure 1 is a plan view of one form of machine of this class with my improvement attached. Fig. 2 is a front elevation of a part of the same. Fig. 3 is a side elevation of a part of the machine. Fig. 4 is a side view of the jointed arm; and Fig. 5 is a detail of the circuit-closer on the end of the traveling lever.

In the drawings my improvement is illustrated as applied to a machine the bed of which has an upright frame *a*, to which is pivoted a segmental gear *b*, that is oscillated horizontally by means of a lever *c*, which travels over a character-index *d*. This segmental gear meshes with a gear *e*, that is pivoted to the back of the frame *a*, so as to oscillate vertically, and secured to the back of this so as to oscillate with it are the disks *g*, the disk *g* being slotted to properly guide and direct the movement of the hammer against the back of the type, which type are flexibly secured to the disk *g*, so that under the impact of a blow from the hammer or

plunger *h* a character will be printed upon paper carried across the machine in the paper-carriage *i*, which is moved by any common ratchet-and-pawl mechanism. The desired character to be printed is of course brought into position by the movement of the lever *c* across the index, the gears transmitting the motion to the type-wheel.

The lower end of the lever bearing the hammer or plunger *h* is forked, as at *h'*, and this fork is pivoted to a part of the upright frame *a*, so as to oscillate back and forth when it is desired to print a character. Projecting down from one arm of the fork is the arm *l*, to which the plate *m* is so connected as to be capable of independent movement backward, swinging on the pivot *o*, but so that it is held as one piece to the arm *l* when the plate *m* is pulled forward, the pin *m'*, fast to the plate *m*, striking the bottom of the slot *l'* in the end of the arm *l*, in which position it is normally held by the spring *m*², holding the parts *l* and *m* together. The lower edge of the plate *m* has an inclined surface or rib *n* for a part of its length, and between the upper end of the rib and the bottom of the arm *l* is a channel *n'*.

The lever *p* is so pivoted to a post that rises from the bed of the machine as to have a vertical oscillation, one end of the lever being so bent as to lie in the path of movement of the printing-key lever *q*, while the other end, under the influence of the spring *p'*, lies under the inclined rib on the plate *m*.

In writing with the machine, when the printing-lever *q* is depressed the outer end of the lever *p* is also depressed with a consequent rising of the inner end, which, coming in contact with the incline on the plate *m*, forces the plate forward out of its way. This causes the arm to be thrown forward and the hammer backward, so that the hammer strikes the back of a type and produces an imprint on the paper. When the end of the lever reaches the cut-away portion of channel *n'* at the end of the incline, the arm is allowed to return to its normal position, which of course pulls the hammer back from the type and out of the slots in the disk *g*, so that the index-lever can be turned to the next character to be printed. When the lever *q* is allowed to

rise, the spring p' forces the end of the lever p down, the top face of the inclined rib of the plate m causing the latter to move out of the way, the said plate m having an independent 5 movement backward, as before stated. As soon as the end of the lever is free from the incline the spring m^2 returns the plate to position for another action.

The construction so far described is that of 10 a machine hitherto patented, (August 20, 1889, No. 409,289,) and is simply referred to herein as one form of machine to which my invention now to be described may be applied.

R indicates an electro-magnet secured to 15 the base or bed of the machine, and its armature R' is pivoted at r to an upright or to the frame a . The armature has an extension r' , projecting over the end of printing-lever q , in order that when the magnet is energized 20 the armature thereof will operate said printing-lever.

The handle of lever c has an ordinary push-button c' , and from the two contacts thereof wires insulated from each other pass to or 25 nearly to the center of motion of said lever, so as not to interfere with its operation, and thence to the magnet, the circuit including of course some source of electrical energy, as a battery at c^2 . In operation the lever c will be 30 moved to locate the type, and then a pressure on the push-button will complete the circuit and cause the magnet to operate the hammer through the medium of its armature and the means hereinbefore described. It is obvious 35 also that by providing a space on the char-

acter-index, to which the lever c can be moved and the hammer operated without making an impression, the spacing-lever may be dispensed with. For instance, if one of the types were omitted, when the lever c is moved to 40 that position on the index and the circuit closed no impression will be made, but the usual mechanism will feed the paper.

I do not limit myself to the exact form of 45 type-writer herein shown to which to apply my improvement, as it can be adapted without the exercise of invention to other type-writers of this class.

Having thus described my invention, I 50 claim—

In a type-writing machine, the combination, 55 with type-locating mechanism, of a lever for operating said mechanism, a hammer for making the impression, an electro-magnet for operating the hammer, a push-button carried by the outer portion of the lever, and two electrical connections carried from the two contacts of the push-button along the lever toward its center of motion and thence to the magnet, the circuit formed thereby including 60 a source of electrical energy, substantially as described.

In witness whereof I have hereunto signed my name in the presence of two subscribing witnesses.

EDWARD F. YOUNGS.
